UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

SEWING AND RUFFLING MACHINE.

1,115,145.

Specification of Letters Patent. Patented Oct. 27, 1914.

Application filed July 14, 1903. Serial No. 165,491.

To all whom it may concern:

Be it known that I, RUSSEL G. WOODWARD, a citizen of the United States, residing at Waukegan, in the county of Lake, State of Illinois, have invented certain new and useful Improvements in Sewing and Ruffling Machines, of which the following is a description, reference being had to the accompanying drawing and to the letters and figures of reference marked thereon.

My invention relates to an improvement in sewing and ruffling machines of the type known as the Union Special type, such as illustrated more particularly in my Patent No. 635,143, of July 31st, 1900.

The object of the present invention is to provide a machine of the type referred to, in which the ruffler and the parts coöperating therewith, such as the folder, stripper blade, and edge guide, may all be thrown out of operation without disturbing the action of the stitch-forming mechanism.

The invention has been especially designed for use in connection with skirt and petticoat sewing and ruffling machines, in which a ruffle or series of ruffles is to be secured to the body of the skirt, and it is desirable to throw out the ruffling apparatus to enable the operator to end the same where it began, without the interference of the ruffling piece, although, of course, the invention is applicable to any machine for sewing and ruffling tubular goods.

In an application heretofore filed by me on the 9th day of April, 1903, Serial No. 151,826, I have shown, described and claimed, a machine adapted for this purpose, and the present invention relates to certain improvements thereupon, which makes the machine more practicable.

In brief, the improvements which I have developed after the machine referred to in the former application has been in practical operation for some time, involve certain mechanism whereby in the operation of throwing the ruffler and the parts coöperating therewith into and out of action, the presser foot will first be raised to enable the ruffling device to be moved from under it, and also back under it again. In the former machine, this was accomplished with the regular foot-lifting device, but in the present machine mechanism is provided for successively operating the presser foot-lift-

ing device, and then the device for throwing the ruffler parts into and out of operation. It has also been found in practice, that the ruffler blade being spring-pressed against the stripper blade held on to the material which was clamped between these two blades when the ruffle was thrown out of the seam, and, therefore, it has been found desirable to provide mechanical means for raising the ruffler blade automatically, as the ruffling mechanism is moved sidewise and upward, these devices also working when the ruffler is moved into the seam.

With this brief outline of the improvements which have been made to the former machine, I would state that the invention consists in the various devices for carrying the improvements into effect, and in the matters hereinafter described and referred to in the appended claims.

The invention is illustrated in the accompanying drawings, in which,

Figure 1 is a perspective view of a ruffling and sewing machine, embodying my invention, the parts being shown in the position they assume when ruffling and sewing are to be performed; Fig. 2 is a rear elevation of the machine, showing the parts in similar position; Fig. 3 is a front elevation showing the position of the parts when the ruffler and parts coöperating therewith, such as the folder, edge guide, and stripper blade, are thrown out of operation; Fig. 4 is an end view of Fig. 1; Fig. 5 is a rear detail view, showing the position of the parts during the first operation of the cams, that is, the presser foot having been raised, the outward movement of the ruffler, and the parts coöperating therewith not having yet taken place; and Fig. 6 is a detail view showing the positions of the cams when the ruffler is thrown out of position. Fig. 7 is a detail perspective showing the cams.

In these drawings, 1 represents the main shaft, from which motion is imparted to the horizontal transverse bar 19, sliding in lugs 20 on the bracket 2. The ruffler blade supporting head 22, is attached to the end of the transverse sliding bar, and to the bracket 2 is attached the stripper blade support, the folder support and the edge guide support, these parts being of the usual construction.

Upon the forward end of the rock shaft

15 is fixed a head 6, having two arms 7, extending downwardly therefrom, the opening between them being wider at the top than at the bottom, the width of the space 5 at the bottom being sufficient to receive snugly the arm of the lever 8, which has a link connection 18 with the sliding bar 19, and at its upper end is pivoted to the lower end of the fork 9, pivoted on a sleeve 10, 10 surrounding the rock shaft, and held in place by two collars 100, adjustably secured on the rock shaft. Upon the opposite or front side of the head of the machine is pivoted at 11, upon an adjustable block 110 15 on the overhanging arm, another arm or lever 12, which is attached to the bracket 2. When the arms or levers 8 and 12 are swung up on their pivots the arm or lever 8 moves up out of the narrow space in the vibrating 20 yoke, formed by the arms 7, 7, and the wider part of said space in the yoke is sufficient to allow vibration of said yoke, without contact with the arm 8, thus when said arms are swung up on their pivot the sliding of 25 the arm 19 ceases, and, therefore, the ruffler stops.

The swinging of the arms 8 and 12 on their pivots, and consequent stopping of the ruffler and the throwing of all the parts 30 which coöperate with the ruffler, out from in front of the needle, to enable the operator to join the edges of the tube, as also the raising of the presser foot P, which is supported on the presser bar P', and which is 35 connected with a supplemental presser bar P² is accomplished by the following mechanism: Journaled in a suitable bearing lug A on top and at the rear of the overhanging arm or goose neck of the machine is a shaft 40 or rod B, having at the front of the machine a handle C, to enable it to be manipulated, and on this shaft B is a segment D having projections a, adapted to engage a stopping member b, in the extreme positions to which 45 the handle is turned. The hand shaft B is provided in rear of the goose-neck or overhanging arm, with a cam E which in the movement of the shaft is adapted to come in contact with the ordinary presser foot 50 lever F, and force the rear end of the latter downwardly, thereby raising the presser foot against the action of its spring, the ordinary flat presser foot spring G in the present case being supplemented by a coil 55 spring H. The cam E is of such shape that when the handle is pulled toward the head of the machine, said cam first raises the presser foot, and then when it passes by the dead center, releases it and allows the 60 presser foot to fall upon the fabric, and in the movement of the cam from the position shown in Fig. 6 to its normal position, the presser foot is first raised, and then allowed to fall. Adjacent the cam E, but nearer the 65 outer end of the shaft B is arranged a second

cam I, which is of the shape shown and adapted to act after the cam E has given the initial rise to the presser foot, to bear upon the lever 14, which is pivotally connected at its front end to the rod 13, pivoted to the bracket 2 at its lower end. Upon the outer end of the shaft B is an arm K, carrying at its lower end a segment L, which is formed as shown, and is provided with the cut out portions M and N, with a shoulder O between them. Near the rear end of the lever 14 is a pin d, which when the parts are in normal position fits behind the shoulder O, as shown in Fig. 2, and prevents accidental displacement. 70

When the parts are moving from the position shown in Fig. 2, to the position shown in Fig. 3, the pin d runs in the cut out portion M, while the cam I is forcing down the end of the lever 14, and raising the ruffler and connected parts out of engagement. When the parts return, however, to the normal position, the pin d strikes the cut out portion M, about the time that the cam I releases the lever 14, and by the action of the part L against the pin forces up the rear end of the lever 14, thus forcing the parts back to operative position. It will be seen that in this arrangement, the presser foot spring or springs are of considerable importance, 85 inasmuch as it is against the pressure of the said spring or springs that the cams operate. 90

I have found it desirable to obviate the clamping of the ruffler blade against the 100 stripper blade 25 when the ruffler is being thrown out of the seam, to provide means for lifting the ruffler blade from engagement with the stripper blade, as the presser foot begins to rise, and to accomplish this object, I have attached to the ruffler head 22 pivoted at 23, a projection f, which is adapted to engage a notch e formed in an angle arm Q, 105 adjustably secured to the angle iron R, which is attached to, and moves with, the presser foot. It will be seen, therefore, that when the parts are in operative position, as shown in Fig. 1, if the handle C is manipulated, the presser foot is first raised, and in the raising the ruffler blade support will be tilted, and then in the further movement of the handle the projection f will be forced out of the notch e, and in the return position will first engage said notch, and be tilted until the presser foot falls to proper position. By this arrangement, all danger 110 of clamping the material between the ruffler blade and stripper blade is avoided, when the ruffler mechanism is moving in or out. 115

It will be understood that I do not wish to be limited to the details of construction herein set forth for operating the presser foot, and throwing out the ruffler mechanism; that is, I do not wish to be limited to the cam arrangement shown, as any means 120 125 130

which successively raise the presser foot, and then throw out the ruffling mechanism may be included within the scope of my invention. So also, as to other features, I
5 do not wish to be limited to the details of construction, as various minor modifications and changes may be made, without departing from the spirit of my invention.

Having thus described my invention, what
10 I claim as new, and desire to secure by Letters Patent, is:—

1. In a sewing machine, a presser foot, a ruffling mechanism with means for operating the same, and means for successively raising the presser foot and throwing the ruffler into operation and for successively raising said presser foot and throwing the ruffler out of operation; substantially as described.

2. In a sewing and ruffling machine, a presser foot, means for successively raising the presser foot and throwing the ruffler out of action, means for lowering the presser foot, and means for successively raising the presser foot and throwing the ruffler into action; substantially as described.

3. In a sewing and ruffling machine, means for operating the ruffler, a presser foot, means under the control of the operator for successively raising the presser foot and throwing the ruffler out of operation, and for successively raising the presser foot, and throwing the ruffler into operation; substantially as described.

35 4. In a sewing and ruffling machine a supporting frame, a ruffling mechanism attached to a support pivoted on the frame, a lever for operating said support, a presser foot, a lever for operating the same, and means for successively operating said levers; substantially as described.

45 5. In a sewing and ruffling machine a supporting frame, a ruffling mechanism attached to a support pivoted to the frame, a lever for operating said support, a presser foot, a lever for operating the same, and a shaft provided with a series of cams successively operating upon said levers; substantially as described.

50 6. In a sewing and ruffling machine, the combination of a presser foot, devices for lifting the presser foot, a ruffling member, devices for throwing the ruffling member into and out of operation, cams for successively engaging respectively the devices for raising the presser foot and the devices for throwing said ruffling members into and out of operation, and means for operating said cams.

60 7. In a sewing and ruffling machine, a presser foot, a lever connected to the same, a ruffling device, a lever connected to the same, and a shaft having a series of cams successively engaging the said levers; substantially as described.

8. In a sewing and ruffling machine, the combination of a presser foot, a ruffling device, a stripper blade, a support for the ruffling device and stripper blade, and a device under the control of the operator having members for successively engaging and raising the presser foot, and engaging the ruffling device for separating the same from the stripper and for throwing said ruffling device out of operation.

9. In a sewing and ruffling machine, a ruffling device, a presser foot, and a spring for normally holding the presser foot and ruffling device in operative position, and means for successively raising the presser foot and ruffling device out of operation against the action of the spring, and means for moving the ruffling device in a direction transverse to the direction of reciprocation of the needle; substantially as described.

10. In a sewing and ruffling machine, a ruffling device, a presser foot, a spring for normally holding the presser foot and ruffling device in operative position, means for successively raising the presser foot and ruffling device out of operation against the action of the spring, means for moving the ruffling device in a direction transverse of the reciprocation of the needle and means for preventing the last named movement of the ruffling device without lifting the presser foot; substantially as described.

11. In a sewing and ruffling machine, having stitch forming mechanism including a vertically reciprocating needle, a ruffling device, a presser foot, and a spring for normally holding the presser foot and ruffling device in operative position, and means for successively raising the presser foot and ruffling device out of operation against the action of the spring, and means for moving the ruffling device in a direction transverse to the direction of reciprocation of the needle, and means for holding said ruffling device in inoperative position; substantially as described.

12. In a sewing and ruffling machine, a ruffling mechanism including a pivoted ruffler blade support, a pivoted frame work upon which the same is supported, a presser foot, means for successively raising the presser foot and swinging the pivoted framework, a presser bar, a connection between the presser bar and ruffler blade support, whereby as the presser foot is raised the ruffler blade is tilted, and in the outward movement of the framework the connection between the presser bar and ruffler blade supporting head is broken; substantially as described.

13. In a sewing and ruffling machine, a pivoted supporting frame work, a ruffling blade carried thereby, with means for operating the ruffling blade, a presser foot, a cam shaft provided with a series of cams for

successively operating the presser foot and pivoted framework; substantially as described.

14. In a sewing and ruffling machine, a pivoted supporting framework, a ruffling blade carried thereby, with means for operating the ruffling blade, a presser foot, a cam shaft provided with a series of cams for successively operating the presser foot and pivoted framework, and having a segment adapted to engage and hold the parts in locked position; substantially as described.

15. In a sewing and ruffling machine, a pivoted supporting framework, a ruffling blade carried thereby, with means for operating the ruffling blade, a presser foot, a cam shaft provided with a series of cams for successively operating the presser foot and pivoted framework, and having a segment adapted to engage a pin carried by one of said parts to hold said parts in locked position; substantially as described.

16. In a sewing and ruffling machine, a pivoted supporting framework, a ruffling blade carried thereby, a lever attached to said framework, and having a pin projecting therefrom, a presser foot, a lever for operating the same, a cam shaft provided with a series of cams for successively engaging the two levers, and carrying a segment with cut out portions adapted to engage the pin successively; substantially as described.

17. In a sewing and ruffling machine, a presser foot, a ruffling mechanism including a stripper blade and a ruffling blade, means for separating said stripper blade and ruffling blade and for moving said ruffling mechanism in a direction transverse to the line of the seam out of operative position; substantially as described.

18. A sewing machine, a presser bar, a presser foot, a ruffling device, means carried by said presser bar for engaging the ruffling device, means for operating said ruffling device, means for throwing said ruffling device into and out of operative position, said means for connecting the ruffling device to the presser bar being disengaged, when the ruffling device is thrown out of operative position and brought into engagement when said ruffling device is thrown into operative position; substantially as described.

19. In a sewing and ruffling machine, the combination of a work support, a supporting frame, a ruffling device, means for pivoting said ruffling device on said supporting frame, a movable bar, a presser foot carried by said inovable bar, and means comprising a single member actuated by the operator to successively raise the presser foot and move the ruffling device in a direction transversely to the line of seam into and out of operative position.

20. In a sewing and ruffling machine, a ruffling device pivoted on the machine frame, a presser foot mounted on a movable bar and means comprising a single member to be actuated by the operator to raise the presser foot and throw the ruffling device into and out of action, and independent means for tilting the ruffling blade; substantially as described.

21. In a sewing machine, a ruffling device means for operating the same, a presser foot, means for successively raising the presser foot, and throwing the ruffling device into and out of operative position, and means for preventing the throwing of the ruffling device, out of operative position unless the presser foot is raised; substantially as described.

22. In a sewing and ruffling machine, a ruffling mechanism, means for moving said mechanism in a direction transverse to the line of the seam, and means for tilting the ruffling blade as the device starts to move in the direction transverse to the line of the seam.

23. In a sewing and ruffling machine, a ruffling mechanism attached to a support pivoted to the machine frame, a lever for operating said support, a presser foot, a lever for operating the same and a shaft provided with a series of cams operating upon said levers; substantially as described.

24. In a sewing and ruffling machine, a presser foot, a ruffling device and a cam and lever mechanism engaging the presser foot and ruffling device to successively raise the former and move the latter in a direction transverse to the line of the seam into and out of operative position.

25. In a sewing and ruffling machine, a pivoted supporting framework, a ruffling blade carried thereby, with means for operating the ruffling blade, a presser foot, a cam shaft, provided with a series of cams for operating the presser foot and pivoted framework and having a segment adapted to engage and hold the parts in locked position; substantially as described.

26. In a sewing and ruffling machine, a pivoted supporting framework, a ruffling blade carried thereby, with means for operating the ruffling blade, a presser foot, a cam shaft provided with a series of cams for operating the presser foot and pivoted framework and having a segment adapted to engage a pin carried by one of said parts to hold said parts in locked position; substantially as described.

27. In a sewing and ruffling machine, a pivoted supporting framework, a ruffling blade carried thereby, a lever attached to said framework and having a pin projecting therefrom, a presser foot, a lever for operating the same, a cam shaft provided with a

series of cams for engaging the two levers and carrying a segment with cut out portions adapted to engage the pin; substantially as described.

28. A sewing and ruffling machine including in combination, a presser foot, a presser bar, a ruffling device, means for successively raising said presser foot, moving said ruffling device out of operative position and lowering said presser foot with said ruffling device held in inoperative position; substantially as described.

29. A sewing machine and ruffling machine including in combination a presser foot, a ruffling device, means for moving said ruffling device into inoperative position, means for raising the presser foot returning said ruffling device to operative position and lowering said presser foot and holding said ruffling device in inoperative position while the presser foot is lowered; substantially as described.

30. A sewing and ruffling machine including in combination a ruffling device, comprising a ruffling blade and a stripper blade, and means for separating said ruffling and stripper blades, and moving said ruffler device in a direction transverse to the line of the seam to inoperative position; substantially as described.

31. A sewing and ruffling machine including in combination a presser foot, a ruffling device comprising a ruffling blade and a stripper blade, and means for raising said presser foot, separating said ruffling and stripping blades, moving said ruffling device to inoperative position and lowering said presser foot and holding said ruffling device in inoperative position while the presser foot is lowered; substantially as described.

32. An attachment for sewing machines, comprising ruffling mechanism, the said mechanism when in operative position arranged to be operated by a moving part of the machine, and means for shifting said mechanism laterally, the said means con-

sisting of a lever pivoted to a rigid part of the machine; substantially as described.

33. A ruffling attachment for sewing machines, comprising a pivoted ruffling blade, means for raising the free end of said blade from the work, means for shifting the same laterally, and means operated by a moving part of the machine for reciprocating said blade during its ruffling operation; substantially as described.

34. The combination with a sewing machine, of a ruffling mechanism located normally at one side of the line of feed, means to shift said ruffling mechanism laterally, and means to lower the ruffling blade when the same is over the line of feed; substantially as described.

35. In a sewing machine, the combination with a presser foot, of a ruffler blade, means to reciprocate said blade to gather the material and force it under the presser foot, and means to raise the said ruffler blade and simultaneously move the same laterally out of the line of feed; substantially as described.

36. A ruffling attachment for sewing machines, comprising a ruffling blade, means for raising the free end of said blade from the work, and simultaneously shifting the same laterally, and means operated by the moving part of the machine for reciprocating said blade during its ruffling operation; substantially as described.

37. In a sewing machine, a presser foot, a ruffling mechanism including a ruffling blade and a stripper blade, means for successively raising the presser foot and throwing the ruffler out of operation, and means simultaneously operable with the raising of the presser foot, for separating the ruffling and stripper blades.

In testimony whereof I affix my signature in presence of two witnesses.

RUSSEL G. WOODWARD.
